UNITED STATES PATENT OFFICE.

ARTHUR H. ANDREWS, OF WILLIAMSPORT, PENNSYLVANIA.

DESIGN FOR A BICYCLE-FRAME.

SPECIFICATION forming part of Design No. 27,767, dated October 19, 1897.

Application filed August 4, 1897. Serial No. 647,128. Term of patent 14 years.

To all whom it may concern:

Be it known that I, ARTHUR H. ANDREWS, a citizen of the United States, residing at Williamsport, in the county of Lycoming and State of Pennsylvania, have invented and produced a new and original Design for Bicycle-Frames, of which the following is a specification, reference being had to the accompanying drawing, forming a part thereof.

10 The figure of drawing represents my bicycle-frame in side elevation.

As shown in the drawing, the leading or material feature of my design consists in the bowed section A at the rear of the straight seat-post B. This curved section A is in the 15 arc of a circle, except the portion D, adjacent to its point of attachment to the shaft-hanger

C, which is practically straight. This part A is attached at its end *a* to the seat-post B, near the top thereof, while the other end *b* of said part A joins the shaft-hanger C. Extending from the post B to the part D of section A is the brace E, and projecting upwardly from the lower portion of section A are the bearings F.

Having described my invention, what I claim as new, and desire to secure by Letters Patent, is—

The design for a bicycle-frame, as herein shown and described.

ARTHUR H. ANDREWS.
